UNITED STATES PATENT OFFICE.

FREDERICK W. SAUER, OF BROOKLYN, NEW YORK, ASSIGNOR TO HOME DEVICES CORPORATION, OF BROOKLYN, NEW YORK, A CORPORATION.

LAUNDRY APPARATUS.

1,224,963.

Specification of Letters Patent. Patented May 8, 1917.

Application filed December 15, 1915. Serial No. 66,901.

To all whom it may concern:

Be it known that I, FREDERICK W. SAUER, a citizen of the United States, residing in the borough of Brooklyn, county of Kings, and State of New York, have invented new and useful Improvements in Laundry Apparatus, of which the following is a specification.

The invention relates to laundry apparatus, and more particularly to tubs suitable for domestic use. The object is to provide a tub and stand of strong and inexpensive construction, in which the tub is provided with an efficient pouring structure, and, while held perfectly steady during use, may be easily tilted to discharge the wash water in an advantageous manner. With these ends in view the invention may be said to comprise the features and combinations hereinafter described and more particularly pointed out in the appended claims.

In the drawings forming a part hereof:

Figure 1 is a side elevation of the tub and stand, the tilted position of the tub being indicated by broken lines;

Fig. 2 is a rear elevation, certain parts of the apparatus forming no part of the present invention being indicated in dotted lines;

Fig. 3 is a plan view;

Fig. 4 is a fragmentary sectional bottom plan view;

Fig. 5 is a fragmentary vertical section on the line 5—5 of Fig. 1;

Fig. 6 is a fragmentary section on the line 6—6 of Fig. 3; and

Fig. 7 is a view looking horizontally at the inside of the upper part of the front of the tub.

The stand comprises two elongated triangular side frames 1, between which the tub 2 is tiltably suspended. The front and rear members 3 and 4 of each of said side frames are preferably formed of angle iron with suitable feet 5 at their lower ends, and are connected by diagonal crossed braces 6. The rear members 4 of the frames are connected with each other directly below the tub by a cross-piece 7, and the two frames are further connected and braced near the bottom by tie members 8, which are secured at their outer ends to the lower portions of said members and are carried diagonally inward from the four corners of the base 55 of the stand to the center, where they are

united by rivets 9, as shown in Figs. 1 and 3. As thus constituted the stand is of strong and durable construction, presents no parts in the path of the flow from the tub when the latter is tilted, and has the further advantage of affording a recess 60 within its front portion wherein a receptacle may be placed, as indicated at 9' in Fig. 1, directly below the forward half of the tub in position to receive the discharge 65 therefrom.

In the practical embodiment of the invention the tub is of sheet metal construction, of oblong form, with a curved bottom. At the top it is provided with an outwardly 70 projecting rim 10, of hollow boxed construction, constituting an effective reinforcement. At the ends of the tub strap irons 11 are secured below the overhang of the rim, and carry bearing blocks 12, which receive hollow journals 13 held by set screws 14 in blocks 15 secured to the apexes of the frames 1.

When in use the tub is held steady by means of a detent 16 which comprises a strip 80 of resilient metal secured at its upper end to the cross-piece 7, as indicated at 17, and at its lower end being provided with a pedal 18 disposed near the bottom and one end of the stand. The upper portion 19 of the said strip is bent laterally, and this portion is formed with an opening 20, which normally receives a pin 21 projecting downward from a plate 22 fast on the under side of the tub. Downward pressure applied to the pedal 18 lowers the apertured portion 19, thereby 90 freeing the tub, so that it may be tilted. When the pressure is removed the detent returns to holding position by virtue of its resiliency.

Centrally of the front of the tub the rim 10 is formed on its inner side with an inclined notch or recess 23, this notch being included within the continuous lines of the rim and constituting a non-projecting pouring lip. In conjunction therewith a spout top 24 is provided over the forward portion of the interior of the tub, the said top comprising a flange projecting inward from the front wall of the tub opposite the rim and 100 extending in either direction from the notch 23 to the end walls. The said flange is preferably widest at the ends and inclines upward from both ends toward the center, 110 its middle portion 25 opposite the pouring

lip 23 being offset upwardly and preferably notched at its forward edge, as at 26, in order to afford free egress for water.

An angle piece 27, secured to a cross-bar 5 28 on one of the side frames 1, constitutes a stop in the path of the rim 10 to limit the tilting of the tub to a degree which is advantageous for pouring.

In case the foot pedal 18 should be partly 10 depressed or the pin 21 should tend to slip out of its opening 20 as the tub is being raised to its normal position after being emptied, a lock is provided to keep the tub from tilting in the reverse direction and 15 consists of a small lug 32 projecting from the plate 22 and a stop member 33 secured to the detent 16, said stop member 33 to engage with the lug 32 when the tub is in the upright position.

20 What is claimed as new is:

1. In a wash tub, a stand, a tub tiltably supported therein and having an outwardly projecting continuous top rim, said rim having an inclined notch formed in its inner

side within the lines of the rim so as to 25 constitute a non-projecting pouring lip, and a spout top comprising a flange projecting inward from said rim over the interior of the tub and extending at either side of said notch to opposite side portions of the tub. 30

2. A tilttable wash tub comprising a sheet metal body rectangular at the top and having an outwardly projecting hollow rim of boxed formation, said rim having a beveled recess at its inner side centrally of the front 35 of the tub forming a non-projecting pouring lip, and a spout top comprising a flange projecting inward from the top of the front of the tub and extending from side to side thereof, said flange being inclined upward 40 from both ends toward the middle, and having its central portion opposite said notch upwardly offset from its inclined portions.

Dated November 30th, 1915.

FREDERICK W. SAUER.
